ROYAL C. TAFT, WILLIAM B. WEEDEN, AND JAMES W. TAFT, OF PROVIDENCE, RHODE ISLAND.

Design No. 4,532, dated December 20, 1870.

DESIGN FOR A WOVEN FABRIC.

The Schedule referred to in these Letters Patent and making part of the same.

To all whom it may concern:

Be it known that we, ROYAL C. TAFT, WILLIAM B. WEEDEN, and JAMES W. TAFT, all of the city and county of Providence, in the State of Rhode Island, have originated a new and useful Design for Woven Fabrics; and we do hereby declare that the following specification, taken in connection with the drawing making a part of the same, is a full, clear, and exact description and representation thereof.

Figure 1 is a face view of the cloth.
Figure 2 is a cross section.

Our invention consists in a series of lines parallel with each other, and arranged to form a line-stripe of contrasting color with the ground, in combination with alternate stripes of colored spots upon a plain ground, thereby forming a characteristic design for fancy cassimeres.

In the drawing—

A A represent stripes made up of parallel lines $\alpha\alpha$, brought to the surface of the cloth by the process of weaving, and in color contrasting with the ground.

B B are alternate stripes made up of the plain ground of the fabric, relieved by fine spots formed from colored threads brought to the surface by the

same means as are employed to show the lines $\alpha\alpha$, composing the bands of stripes.

We are aware that goods having a general resemblance to the style herein described have been heretofore made, in which alternating series of lines and spaces have been exhibited; but such lines have been made from more than one thread in the warp, and of varying widths.

We consider our design far more delicate and artistic, and therefore do not claim a general design for lines and spaces; but

What we do claim is—

The design herein described, consisting of the single-threaded lines $\alpha\alpha\alpha\alpha$, of equal sizes, of a contrasting color, equidistant, and arranged in series, A, separated by spaces B, having a corresponding width with the series A, and relieved by spots of a contrasting color.

ROYAL C. TAFT.
WM. B. WEEDEN.
JAMES W. TAFT.
